UNITED STATES PATENT OFFICE.

ORVAL T. JOHNSON, OF MURPHYSBORO, ILLINOIS.

AUTOMATIC PRESSURE-RETAINER.

1,006,223.

Specification of Letters Patent. Patented Oct. 17, 1911.

Application filed May 12, 1911. Serial No. 626,876.

To all whom it may concern:

Be it known that I, ORVAL T. JOHNSON, a citizen of the United States, residing at Murphysboro, in the county of Jackson and State of Illinois, have invented new and useful Improvements in Automatic Pressure-Retainers, of which the following is a specification.

This invention relates to an automatic pressure retainer for air-brake systems, and its object is to provide a pressure retaining device whereby the exhaust of the triple valve is placed under the control of the engineer, so that the train line and auxiliary 10 reservoirs may be recharged to normal pressure while the brakes are set, allowing a train in descending heavy grades to be held completely under control.

A further object of the invention is to 20 provide a pressure retainer which is accurate and sensitive in action, simple and comparatively inexpensive of construction, and free from complicated parts liable to get out of order.

25 The invention consists of the features of construction, combination and arrangement of parts, hereinafter fully described and claimed, reference being had to the accompanying drawings, in which:—

30 Figure 1 is a view in elevation, showing the application of the invention. Fig. 2 is a sectional view through the retainer, showing the parts in the position they assume after the application of the brakes and before the train line is recharged. Fig. 3 is a view similar to Fig. 2, showing the parts in brake-releasing position. Figs. 4 and 5 are sections on the lines 4—4 and 5—5 of Fig. 2.

The retainer comprises a pair of superposed cylinders 1 and 2, preferably made in a single casting, and disposed with their axes out of longitudinal alinement, but in parallel relation, as shown. The lower cylinder 1 is adapted to receive the exhaust of 40 fluid pressure from the triple valve casing, and is provided at its lower end with a neck or reduced extension 3 through which extend air feed passages 4 and 5. The passage 4 communicates with the lower end of the cylinder 1, while the passage 2 extends upwardly through the side of the cylinder 1, base of the cylinder 2, and thence up through

the side of the cylinder 2 to the top of said cylinder. The neck 3 is coupled by a suitable connection 6 with the exhaust port of the 55 triple valve 7, said valve affording communication between the triple valve exhaust and the feed passage 4, while the feed passage 5 is in communication with a branch pipe 8 leading to the train line. In practice, 60 the cylinders are preferably vertically arranged and are provided with flanges or suitable projections 9, whereby they may be bolted or otherwise fastened to the locomotive or railway car to which the device is to 65 be applied.

The passages 4 and 5 are controlled at their inlet ends by a plug valve 10 provided with ports 11 and 12 for communication therewith, whereby the retainer may be 70 thrown into and out of action whenever desired. In the connection 6 is a valve 10^a which is open, when the valve 10 is closed to cut out the retainer, to permit free exhaust from the brake cylinder to the atmosphere. 75

Arranged for movement within the cylinder 1 is a piston valve 13, of proper weight to be raised at about twenty pounds pressure, the usual pressure of the exhaust from the triple valve. This piston valve is fixed upon 80 the lower end of an upwardly extending stem 14 which is slidably mounted in the upper head of said cylinder and in a guideway 15 formed in the wall of the cylinder 2. In said piston valve is formed an angular 85 passage 16 having its inlet end opening through its base for connection with the cylinder below said valve and its exhaust end opening through the periphery of the valve and adapted for communication with a discharge port 17 formed in the wall of the cylinder 1 at a suitable point below the top thereof.

Surrounding the upper end of the stem 14 and supported by the upper head of the 95 cylinder 1 is a coiled cushioning spring or buffer 18 against which the valve 13 bears when elevated approximately to its limit by the air pressure behind it. This spring opposes further upward movement of the valve 100 and tends to maintain it in proper position to hold the ports 16 and 17 in registry, for the exhaust of the fluid pressure from the cylinder 1.

Arranged within the cylinder 2 is a piston or head 19 which is subjected to the force of the train line pressure entering said cylinder through the feed passage 5. From 5 this piston head depends a stem 20 slidably mounted in the lower head of said cylinder 2 and in a longitudinal guide way 21 formed in the side of the cylinder 1 in parallel relation to the feed passage 5, which guide way 10 21 is in communication with the port 17 and with a final exhaust port 22 leading to the atmosphere. The stem 20 operates as a valve controlling the port 17, and is provided with a port or opening 23 there- 15 through adapted to register with said port 17 when the piston 19 is depressed to its limit, whereby the fluid pressure is permitted to exhaust from the cylinder 1 to the atmosphere. A spring 24 is carried by the 20 portion of the stem movable in the guide-way or passage 21, and operates to hold said stem in close contact with the surface of the wall in which the port 17 is formed to prevent leakage. The piston head 19 is nor- 25 mally sustained by a coiled spring 25 surround- ing the stem between said piston head and the lower end of the cylinder 2, which spring is of proper strength to hold the piston head against downward movement 30 until the pressure in the train line has reached the normal degree, approximately seventy pounds.

In the operation of the retainer, it will be understood that the retainer on each locomotive or car may be cut out of service whenever required by closing the valve 10 and thrown into operation at any time by opening said valve, whereby communication will be established between the exhaust 35 port of the triple valve and the cylinder 1 and between the passage 5 and the train pipe. As the weight of the gravity piston valve 13 is such as to require a pressure of at least twenty pounds to elevate it, it will 40 be apparent that it will maintain its normal position at the lower end of said cylinder until the pressure of the exhaust from the triple valve is sufficient to raise it to bring the passage 6 into registry with the exhaust 45 port 17. If, under such conditions, the pressure in the train line is below normal, the exhaust of fluid pressure from the triple valve will be prevented through the closure of said port 17 by the valve stem 20, so 50 that the brakes will be held set or applied. The engineer may, therefore, recharge the train pipe and auxiliary reservoir until the pressure in the train line reaches the normal, whereupon the piston 19 will be de- 55 pressed against the resistance of the spring 25 until the port 23 registers with the port 17, whereupon the exhaust from the triple valve will vent to the atmosphere through the port 23. As a full pressure of air is 60 65 now in the brake system, it will be under-

stood that the engineer may again immediately apply the brakes if desired. Hence, it will be seen that the pressure in the brake cylinder may be maintained while the train line is being recharged, giving the engineer thorough and complete control over the train in descending heavy grades. 70

Having thus described my invention, I claim:

1. A pressure retainer comprising a pair 75 of cylinders provided with passages for respective communication with the triple valve exhaust port and the train line of an air brake system, one of said cylinders being provided with an exhaust port, a piston 80 valve movable in said cylinder under the pressure of air from the triple valve and provided with a passage to register with said exhaust port, a downwardly movable piston in the other cylinder provided with 85 a stem controlling said exhaust port, and a spring arranged to prevent depression of said piston until the pressure in said cylinder reaches a predetermined degree.

2. An automatic pressure retainer for air 90 brake systems comprising an exhaust cylinder and a controlling cylinder, said exhaust cylinder being provided with an exhaust port and a passage for communication with the triple valve exhaust, and said control- 95 ling cylinder being provided with a passage for communication with the train line, an upwardly movable piston valve in the ex- 100 haust cylinder having a port to register with said exhaust port and provided with a guide stem movable in guide ways in said cylinder, a downwardly movable piston in the controlling cylinder provided with a depending stem movable in guide ways in said cylinder and having an opening to 105 register with said exhaust port, and a spring arranged to oppose depression of said piston until the train line pressure thereon reaches a predetermined degree.

3. An automatic pressure retainer for air 110 brake systems comprising an exhaust cylinder having an exhaust port and a feed pas- 115 sage for communication with the exhaust port of the triple valve, a controlling cylinder provided with a feed passage for com- 120 munication with the train line, said cylinders being depressed in superposed relation and provided with guide ways, a piston valve in the exhaust cylinder movable upwardly under fluid pressure and provided 125 with a port to register with said exhaust port, a stem projecting upwardly from said valve and movable in one of said guide ways, a cushioning spring arranged to limit the upward movement of said piston valve, a piston in the controlling cylinder movable downwardly under fluid pressure, a stem carried thereby and movable in the other 130 guide way, said stem being provided with a port to register with the exhaust port, a

pressure spring for guiding said stem in a true path, and a spring inclosing the stem and disposed between said piston and the lower end of said controlling cylinder and
5 operating to oppose a determined resistance to the movement of said piston head under the train line pressure thereon.

In testimony whereof I affix my signature in presence of two witnesses.

ORVAL T. JOHNSON.
